CAT SCRATCHING POST

Robin H. Sherwood, 414 E. 65th St., New York, N.Y.
10021, and William A. Forbes, Farmingville Road,
Ridgefield, Conn. 06877

Filed Oct. 24, 1965, Ser. No. 87,893

Term of patent 14 years

(Cl. D12—2)

FIG. 2.

FIG. 1.

We claim:

The ornamental design for a cat scratching post, as shown.
